UNITED STATES PATENT OFFICE

2,553,088

CLAMPING DEVICE

Melray Hoag, Parkwater, Wash.

Application November 18, 1946, Serial No. 710,615

4 Claims. (Cl. 24—250)

1

This invention relates to new and useful improvements and structural refinements in clamping devices and the principal object of the invention is to provide a device of the character herein described, which may be conveniently and effectively employed during the cutting of patches used in the fabrication of so-called "patch work quilts."

Quilts of this character are usually composed of a series of individual pieces or patches of material, connected together by stitching or other means. These patches may be square shaped, diamond shaped, or the like, but in order to assure symmetry and pleasing appearance of the finished article, the patches should be substantially equal in size. Accordingly, a paper pattern is usually employed during the patch cutting operation, such pattern being applied to the material while the patches are being individually cut.

As outlined at the commencement of this specification, the instant invention is particularly adapted for clamping the paper pattern to the material and for releasably retaining the same thereon in such manner as to facilitate convenient and rapid cutting of the patches.

A further object of the invention is to provide a clamping device in which the material and pattern may be readily applied and removed.

Another object of the invention is to provide a clamping device which may be employed in association with materials of different thickness and for cutting patches of various sizes and shapes.

An additional object of the invention is to provide a clamping device in which the clamping block may assume the configuration of the patches, thereby completely eliminating the use of the paper pattern conventionally required.

A still further object of the invention is to provide a clamping device which is simple in construction, convenient in manipulation, and which will not easily become damaged.

With the above more important objects in view, and such other objects as may become apparent as this specification proceeds, the invention consists essentially of the arrangement and construction of parts as illustrated in the accompanying drawings, in which:

Figure 1 is a top plan view of the invention;

Figure 2 is a side elevation thereof, showing the same in the closed position;

Figure 3 is a further side elevational view, similar to that shown in Figure 2, but showing the invention in the open position;

Figure 4 is a cross sectional view, taken sub-

2

stantially in the plane of the line 4—4 in Figure 1;

Figure 5 is a cross sectional view, taken substantially in the plane of the line 5—5 of Figure 1;

Figure 6 is a cross sectional view, taken substantially in the plane of the line 6—6 in Figure 2, and

Figure 7 is a cross sectional view, taken substantially in the plane of the line 7—7 in Figure 2.

Like characters of reference are used to designate like parts in the specification and throughout the several views.

Referring now to the accompanying drawings in detail, the invention consists of a clamping device designated generally by the reference character 10, the same embodying in its construction a pair of arms 11 and 12, including the levers 13, 14 respectively. A pair of side plates 15 are secured at one end of the lever 14 by suitable screws 16 and one end portion of the lever 13 is pivotally mounted between the side plates 15 by means of a suitable bolt 17, as shown in Figure 7.

A leaf spring 18 is secured by suitable screws 19 to the lever 13, the spring engaging the adjacent surface of the lever 14, whereby the two levers are normally urged apart, as will be clearly understood. Excessive spreading of the levers is prevented by means of a yoke 20, the latter straddling the two levers and being formed from a suitable wire-like rod. The end portions 21 of the yoke 20 rotatably engage suitable apertures provided in the lever 14 and it will be noted that the yoke also straddles a pad 22 secured to the lever 13 by a pair of screws 23.

An extension 24 is provided adjacent one end thereof with a longitudinal slot 25, and a bolt 26, secured in the free end portion of the lever 13 passes through this slot and carries a wing nut 27.

A further extension 28 is adjustably attached to the free end portion of the lever 14 by means of suitable screws and wing nuts 29 and 30 respectively, a fulcrum 31 being interposed between the extension 28 and the lever 14, as will be clearly understood. The fulcrum 31 may simply assume the form of a short strap secured to the extension 28 by the screws 32, the strap being provided with an arcuate mid-portion which engages a recess or groove 33 formed in the lever 14.

The free end portions of the extensions 24 and 28 are enlarged to form a pair of mutually opposed jaws 34, the same being provided with op-

posing arcuate surfaces 35 and each being longitudinally slotted as at 36.

The jaws 34 are also provided with axially aligned bores 37, each of which rotatably receives a pin 38. The slots 36 extend through the bores 37 and it will be noted that the jaws are also equipped with suitable clamping bolts 39 whereby the pins 38 may be adjustably secured in position.

Finally, a clamp plate 40 is secured to each of the pins 38, the plate 40 being preferably provided with beveled marginal edges, as will be clearly apparent.

Having thus described the construction of the invention, its method of operation will now be explained.

When the invention is placed in use, the plates 40 are spread apart by simply disengaging the yoke 20 from the pad 22 as shown in Figure 3, thus permitting the spring 18 to spread the levers 13, 14. The material (not shown) may then be inserted between the plates 40, whereupon the levers 13, 14 are compressed together so as to clamp the material between the plates. The device is releasably retained in this closed or clamped position by simply engaging the yoke 20 with the pad 22 and the patch may now be cut from the material by following the contour of the plate 40 with a suitable cutting instrument. It should, of course, be understood that the configuration of the plates 40 conforms in size and shape to the patch, and the cutting operation may be effectively carried out by simply rotating the plates 40 and the pins 38 in the bores 37 of the jaws 34.

Since the mutual spacing of the plates 40 is predetermined and governed by the yoke 20 and pad 22, means are provided for varying this spacing so that material of different thickness may be placed between the two plates. Said means includes the aforementioned fulcrum 31 and the wing nuts 30, the loosening of one wing nut and a corresponding tightening of the other swinging the extension 28 about the fulcrum 31 in one direction, and vice versa. It will be apparent that in this manner, the relative spacing of the plates 40 may be varied as required and furthermore, by loosening the wing nut 27 and sliding the extension 24 with respect to the lever 13, the extension 24 may be adjusted with respect to the extension 28 so that the plates 40 are aligned.

Loosening of the wing nut 27 will also permit the extension 24 to be swung laterally (in the direction of the arrows 41), thereby facilitating removal of the pins 38 and the associated plates 40 from the jaws 34. In this manner, plates of various shapes and sizes may be employed in association with the device for the cutting of variously sized and shaped patches. The clamping screws 39 are provided merely for the adjustment of the jaws 34, so that the pins 38 are rotatably yet firmly mounted in the bores 37.

Finally, the provision of the arcuate surfaces 35 on the jaws 34 facilitates what may be referred to as a rocking contact of the jaws with the plates 40, assuring that equal and unrestrained pressure is applied to the clamping plates.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A clamping device comprising in combination, a pair of levers pivotally connected together at one end thereof, an extension adjustably mounted at the remaining end of each of said levers, a pair of mutually opposed, arcuate jaws provided on said extensions, a pair of axially aligned pins each rotatably mounted in one of said jaws, a pair of mutually opposed clamp blocks each secured to one of said pins and engaging the associated jaw, the adjustment of one of said extensions varying the spacing of said blocks, resilient means for urging said levers apart, and further means for releasably clamping said levers together.

2. A clamping device comprising in combination, a pair of levers pivotally connected together at one end thereof, a longitudinally adjustable extension provided at the remaining end of one of said levers, a further extension fulcrumed upon the remaining lever, the free end portions of said extensions forming mutually opposed, arcuate jaws, a pair of axially aligned pins each rotatably mounted in one of said jaws, a pair of mutually opposed clamp blocks each secured to one of said pins and engaging the associated jaw, means for adjusting the fulcrumed extension whereby the spacing of said blocks may be varied, a spring interposed between said levers, a pad provided on one of said levers, and a clamping yoke pivoted to the remaining lever, said yoke being engageable with said pad.

3. The device as defined in claim 2 wherein said means for adjusting said fulcrumed extension comprise a strap having an arcuate intermediate portion constituting a fulcrum member, end portions of said strap being secured to said fulcrumed extension, the lever carrying said fulcrumed extension being formed with a transverse groove rockably receiving said fulcrum member, and a pair of adjusting screws extending through the fulcrumed extension at the opposite sides of said fulcrum member and engaging the associated lever.

4. The device as defined in claim 2 together with a pivot element connecting said longitudinally adjustable extension to the associated lever whereby said longitudinally adjustable extension may be swung laterally to bring said mutually opposed jaws out of alignment.

MELRAY HOAG.
